UNITED STATES PATENT OFFICE.

THOMAS S. TEW, OF BIG RAPIDS, MICHIGAN.

LOCOMOTIVE.

SPECIFICATION forming part of Letters Patent No. 296,086, dated April 1, 1884.

Application filed June 9, 1883. (No model.)

To all whom it may concern:

Be it known that I, THOMAS S. TEW, of Big Rapids, in the county of Mecosta and State of Michigan, have invented new and useful Improvements in Locomotives; and I hereby declare that the following is a full, clear, and exact description thereof, reference being had to the accompanying drawings, which form a part of this specification.

10 This invention relates to certain new and useful improvements in locomotives especially designed for heavy work; and

15 The invention consists in the peculiar construction and arrangement of parts, by means of which the traction-wheels are converted into drivers, connected fore and aft with the main driver, which is connected to the cylinders, as more fully hereinafter described.

20 Figure 1 is a side elevation. Fig. 2 is a top plan of a section of the parallel rod at its point of connection with the connecting-rod. Fig. 3 is a side elevation of the connecting-rod detached and enlarged. Fig. 4 is an elevation of the driver, double crank, and sections of 25 the fore and aft connecting-rods. Fig. 5 is a front elevation of the main driver, showing its wrist-pin, double crank, and connecting-rod connections.

25 In the accompanying drawings, which form a part of this specification, A represents the main driver provided with wrist-pin B, and is connected with the steam-cylinder C by means of the connecting-rod D in the usual manner. Pivotal secured to the outer end of the wrist-pin B is the arm-crank a; and b b are connecting-rods, one of which is pivotally secured to each end of the double crank a, the connecting ends of such rods being bifurcated, as shown in Fig. 5, so as to embrace both front 40 and rear faces of the crank, to which they are pivotally secured by suitable bolts or pins. One of these connecting-rods, b, connects such 45 crank to the traction-wheels under the fore part of the engine, and another makes a similar connection with the wheels under the engine, and as both connections are alike a description of one will be sufficient. The traction-wheels E are shown in pairs, two being under the front and two under the rear of the

locomotive. These wheels are connected together by parallel bars d in the usual manner of forming such connections between the drivers, and the connecting-rods d are pivotally secured to the vertical center line of the parallel bars by means of the joint e, plate e, and bolts, as more fully shown in Fig. 3, the joint e being so constructed as to allow sufficient play for any inequalities in the surface of the road and for curves, without binding so as to interfere with the proper working 55 of the device. The peculiarity of this joint is that it allows the rod to yield laterally, whereby the binding effect, which would be otherwise caused in turning curves, is effectually done away with.

60 By my invention all the weight of the engine is utilized upon the traction-wheels, the latter being converted into drivers, and hence the locomotive will be found very efficient for heavy work.

65 I attach importance to the pivoted double-crank arms a because their construction allows them to move slightly in passing curves, the one on one side turning slightly in one direction, while the one on the other side turns 70 about equally in the opposite direction; and thus the cramping and binding, which would occur from the moving of the trucks in turning curves, is prevented by the compensation given by the movement of the crank-arms in 75 opposite directions on their centers.

I do not wish to limit myself to the precise number of wheels or construction shown, except where especially indicated in the claims, as it is evident that the number of wheels or 80 the construction may be varied without departing from the spirit of my invention.

85 I am aware that it is not new to provide a connecting-rod with a joint adapted to yield vertically, and make no claim to any such construction.

90 What I claim as my invention is—

95 1. The combination, with the main driving-wheel and crank-pin of a locomotive, of the double-crank arm a, pivotally connected therewith, and the rods b b, connected with opposite ends of said arm, and having their opposite ends connected to driving-wheels on

opposite sides of the main driving-wheel, substantially as described.

2. The combination, with the centrally-located driving-wheels of a locomotive, connected in the usual way to the steam-cylinders, of the double crank *a*, upon the end of the wrist-pin *B*, connecting-rods *b*, the joint *c*, the parallel rods *d*, and the traction-wheels *E*, the parts being constructed, arranged, and operating substantially as and for the purposes specified.

3. The combination, with the main and secondary driving-wheels of a locomotive, of the connecting-rod *b*, having one end provided with a joint, *c*, adapted to yield laterally, and connected at its opposite ends with said main and secondary driving-wheels, substantially as described. 15
